UNITED STATES PATENT OFFICE

2,458,465

CENTRIFUGAL SWITCH

John W. Busacker, Houston, Tex., assignor to the
United States of America as represented by the
Secretary of the Navy

Application September 17, 1943, Serial No. 502,831

1 Claim. (Cl. 200—80)

1

This invention relates generally to safety devices and more particularly to an improved centrifugal switch.

One of the principal objects of the invention is to provide a centrifugal switch of this character which utilizes the power of centrifugal force for closing one or more electric circuits.

Another object of the invention is to provide a centrifugal switch which is of simple construction, and is highly efficient in use.

Further objects of the invention will appear hereinafter.

In the drawings:

Figure 1 is a perspective view of one form of the switch showing its connections in the circuits of an electric system represented by a wiring diagram of an amplifier;

Figure 2 is a horizontal sectional view of this switch;

Figure 3 is a side elevation, portions being shown in dotted lines;

Figure 4 is an enlarged detail sectional view showing one of the contact plungers employed, the spring therefor being shown in full lines;

Figure 5 is a horizontal sectional view showing a modified embodiment, and

Figure 6 is a phantom elevation of the embodiment of the Figure 5.

Referring first to the embodiment shown in Figures 1 to 4, the numeral 1 indicates generally the body of the device which is of circular shape and of proper size and thickness to permit its convenient insertion in the can of a radio proximity fuze. Formed in the body 1 is an axial opening 2 and extending from the axial opening, on equal spaced radii throughout the circumference, are chambers 3, 4 and 5. Each of said chambers communicates with a recess 6 at its outer end, said recess carrying a contact jaw or tubular receptacle 7 which may be the well known cinch contact.

Mounted in the chambers 3, 4 and 5, near their corresponding inner ends, are anchor pins 8, 9 and 10, the purpose of which will be described in more detail hereinafter. Mounted for sliding movement in the chambers 3, 4 and 5 are, respectively, contact plungers 11, 12 and 13, which are, as best seen in Figure 4, in the form of copper cups 14'. Connected between the anchor pins 8, 9 and 10 and the cups 11, 12 and 13 are coil springs 14, one of which is shown in Figure 4. As will be seen, the coil springs are normally contained within the cup, their lower ends being soldered or otherwise suitably secured to the lower end ends of the cup. The upper

2

portion of the springs terminate in linear end portions 15 which are suitably secured to their associated anchor pins.

In use, connections are made from the several circuits as desired to the pins 8, 9 and 10 and to the jaws 7. In the arrangement shown, three electric circuits may be controlled. However, by the use of a greater or lesser number of plungers and associated jaws, a larger or 10 smaller number of circuits may be controlled.

In operation, when the projectile is at rest, the springs 14 will retain the plungers 11, 12 and 13 out of engagement with their associated jaws 7. When the projectile is fired, however, 15 centrifugal force, set up by rotation of the shell, will shift the plungers outwardly, against the tension of the springs 14 into engagement with the jaws 7 for closing the electric circuits.

Referring now to the embodiment shown in 20 Figures 4 and 5, the body is shown at 15. As best seen in Figure 5, the body has three substantially diametrically disposed chambers 16, 17 and 18, which chambers are disposed in vertically spaced relation. Each of the chambers terminates at its outer end in a recess 19 and fitted in the recess are contact members 20 which are formed of soft lead, or some other relatively soft metal.

Positioned near the corresponding inner ends 30 of the chambers 16, 17 and 18 are anchor pins 21, 22 and 23.

Mounted in the enlarged portion of the chambers, which enlarged portions are best seen in Figure 5 at 16a, 17a and 18a, are contact plungers 24, 25 and 26. Each of the contact plungers is formed, at its outer end, with a contact point or nib 27. The plungers are connected with their associated anchor pins by coil springs 28.

40 In operation, when the shell is rotated, centrifugal force will shift the plungers outwardly, against the tension of the springs, for engaging the contact points in their associated contact members 20. Thus, three electric circuits will be closed. As in the first described embodiment of the invention, a greater or lesser number of chambers, plungers, springs and anchor pins may be employed.

It is thought that the construction and operation of both of the embodiments of the invention will now be understood.

What is claimed is:

A centrifugal switch including a flat-sided circular body to be mounted with its axis parallel to an axis of rotation, said body having a plu-

rality of bores disposed at angles with respect to each other and extending substantially diametrically, said bores being in different horizontal planes and having outer ends communicating with the outer surface of the body, fixed contacts of soft metallic material carried in the outer end portions of said bores, said bores being enlarged throughout substantially half their respective lengths, plungers movably carried in the enlarged portions of said bores and having 10 nibs, and restraining springs connected between the corresponding inner ends of the bores and the plungers, said plungers being movable by centrifugal force against the tension of said springs for engaging said nibs in said fixed contacts upon rotation of the body.

JOHN W. BUSACKER.
